International Preliminary Report on Patentability for PCT/US2014/039951, dated Dec. 1, 2015.

Primary Examiner — Ian Simmons*Assistant Examiner* — Samantha Q Lawrence(74) *Attorney, Agent, or Firm* — Locke Lord LLP; Scott D. Wofsy(57) **CLAIM**

The ornamental design for an insertion instrument, as shown and described.

DESCRIPTION

FIG. 1 is a front perspective view of an insertion instrument according to the present disclosure.

FIG. 2 is a rear perspective view of the insertion instrument according to the present disclosure.

FIG. 3 is a top view of the insertion instrument according to the present disclosure.

FIG. 4 is a bottom view of the insertion instrument according to the present disclosure.

FIG. 5 is a front view of the insertion instrument according to the present disclosure.

FIG. 6 is a back view of the insertion instrument according to the present disclosure.

FIG. 7 is a right view of the insertion instrument according to the present disclosure; and,

FIG. 8 is a left side view of the insertion instrument according to the present disclosure.

The broken line areas of FIG. 1-7 are showing portions of the insertion instrument that form no part of the claimed design.
